UNITED STATES PATENT OFFICE.

WILLIAM CAMPION, OF NOTTINGHAM, COUNTY OF NOTTINGHAM, ENGLAND,
ASSIGNOR TO THE AUTOMATIC JACQUARD KNITTING MACHINE COMPANY, (LIMITED,) OF LONDON, ENGLAND.

KNITTING-MACHINE.

SPECIFICATION forming part of Letters Patent No. 251,184, dated December 20, 1881.

Application filed September 29, 1881. (No model.) Patented in England November 21, 1879.

To all whom it may concern:

Be it known that I, WILLIAM CAMPION, of the town and county of Nottingham, England, have invented certain new and useful Improvements in Knitting Machinery for Manufacturing Close or Open Fabrics, of which the following is a specification.

My invention relates to machinery for knitting fabrics; and its object is to do away with the complicated parts which, in machines of the kind hitherto in use, have been used to actuate the fabric-forming devices, with the result of retarding the speed and diminishing the power of the machines.

In the machine embodying my improvements the various bars which carry the working devices—such as the needles, the knocking-over bits, &c.—are carried by and directly connected with oscillating arms, which are governed and actuated by cams, and which impart all needed movements to the fabric-forming devices. The knocking-over bits I construct so that each shall consist of a short upper arm and a longer under arm, and I combine them with the needles, so that they shall act, the shorter arms to hold down the loops on the needles as they rise and the longer arms both to knock over the loops and also as a bed for the fabric and as a sley for the needles. I have also devised a tension device which is simpler and more effective than others hitherto in use, so far as I am aware. In this way I obtain a machine of great simplicity and speed, possessing marked advantages over existing knitting-machines.

The nature of my improvements and the manner in which the same are or may be carried into effect can best be explained and understood by reference to the accompanying drawings, in which—

Figure 1 represents a front view of my improved machinery, portions of the machine being broken away to disclose other parts beyond; Fig. 2, a view at the left end of the same. Fig. 3 is a diagrammatic enlarged view, in cross-section, of the operating parts. Figs. 4 to 14, inclusive, are enlarged views of portions of the apparatus severally referred to hereinafter.

The corresponding parts in each figure are indicated by the same letters where necessary.

The machinery consists of the following parts: two end standards, A A, and, when the length of the machine requires it, one or more intermediate standards or bearings, the whole of which are connected together by two tie-bars, B B, to which and to the standards bearings are secured. The uppermost bearings carry a rocking axle-shaft, C, to which are secured sley bracket arms C', to each of which a slotted bearing, C², is screwed. In these bearings two or more guide-bars, D, slide. Each bar has guide-leads D' secured to it in the usual way, and extending nearly from end to end of the bar. The leads carry either a full set of guides or other number required. A front view of one such guide-lead is shown at Fig. 11. Each guide-bar is traversed endwise by a suitable cam-wheel operating a rocking lever, r, carrying a link, x', at its upper end, attached to the guide-bar, the opposite end of the bar being provided with a spring, y, in the usual way, as indicated in Fig. 1. The back guide-bar is traversed by the cam-wheel D³ (shown in side view at Fig. 8) and the front guide bar by the cam-wheel D², (shown at Fig. 7.) These cam-wheels are varied in shape according to the pattern required. Both wheels are secured on and revolve with a short horizontal shaft, z, lying in bearings secured to the left end standard. The short shaft is provided with a toothed bevel-wheel, D⁴, which gears into a smaller toothed bevel-wheel, D⁵, secured on the left outer end of a cam-shaft, E. The rocking shaft C has one or more truck-bearing levers, D⁶, secured to it, according to the width of the machine. Each lever carries two trucks, which are operated by cams 5 and 6, (shown in side view at Fig. 6.) These cams rock the shaft C so as to cause the guides to pass alternately to the front and back of the needles. Two guide-bars only are shown in the drawings; but I employ a greater number when required, and in either case the lapping-cams 5 and 6 are formed so as to cause the whole of the guide-bars, when being traversed, to clear the needles both at the back and front.

Each slotted bearing C^2 has as many slots as there are guide-bars employed. These bearings are of peculiar construction, having a thin arm projecting at the back, by which they are secured to the sley bracket arms C' . The thin arm allows the threads to reach the guides in a more direct manner than those heretofore constructed. The guide-bars are kept in the slots of the bearings by a plate, C^3 , which lies on the bottom and is screwed to the front of the bearing, as seen at Fig. 3. One such bearing is shown in plan at Fig. 4.

Below the guide-bars is a horizontal bar, F , to the underside of which bearing-levers F' are secured, each of which has its lower end secured to a rocking axle-shaft, F^2 . This shaft has one or more truck bearing levers, F^3 , secured to it, each operated by the cams 3 and 4, (shown in side view at Fig. 5,) which communicate a rocking motion to the horizontal bar.

On the top side of the horizontal bar F are secured plates or leads F^4 , in which knocking-over bits F^5 are soldered or cast. Each of these bits is made of steel wire bent to a U shape and flattened, having one end longer than the other. The shortest ends, being at the top, hold down the loops on the needles as they rise, and the longest ends form a bed for the fabric after it is knocked over. The knocking-over bits also form a sley, in which bearded needles rise and fall. The outer ends of the bits may have a lead cast on them, as shown in sectional view, Fig. 3; or the ends may be inclosed in the fold of a strip of brass, F^6 , as shown in sectional view, Fig. 13, and in plan at Fig. 14. Such strip of brass is kept in position by brass pins, which drop into holes formed for them at about every six inches of its length, each pin taking into a loop formed by the long end of one of the knocking-over bits, as indicated by dotted lines at F^7 in Fig. 14. By such means the strip can be readily removed when a bit lead or plate, F^4 , has to be replaced.

The knocking-over bits, instead of being constructed as above described, may be punched out of thin steel plate; or I may form each length of knocking-over bits by casting leads with short steel bits at the top and long bits at the bottom.

Above the plates or leads a presser-bar, G , is secured. This presser-bar may be either fixed, as shown in the sectional view, Fig. 3, in which case it is made in short lengths to facilitate the removal of the knocking-over leads, or it may be cut away at the front on the top to receive an angular bar, G' , which is arranged so as to slide endwise upon it, as shown respectively in section and plan at Figs. 13 and 14, where the front edges of both the presser-bar G and angular bar G' are provided with "tricks," in which the beards of the needles pass when the tricks in both bars correspond. When a tuck-stitch is required the traverse of the angular presser-bar G' is effected by an

additional wheel, carried by the horizontal shaft z at the left end of the machine, operating a connecting-link attached to the bar, in the same manner as described for traversing the guide-bars.

The bearded needles are cast in leads H , a front view of one of which is shown at Fig. 12, the leads being held to a needle-bar, H' , by plates and screws, in the usual way. The needle-bar is supported by bent bearing-levers H^2 , secured on a rocking axle-shaft, H^3 , to which are attached one or more truck bearing arms, H^4 , each operated by the eccentric cams 1 and 2, (shown in the sectional view, Fig. 3,) causing the needles to rise and fall. The cams for effecting the several movements of the truck bearing levers and their attachments are all carried by the cam-shaft E . Each needle is provided with yarn from one or more guides, each supplied from a spool or warp-beam. In the drawings two warp-beams, $I I$, are shown.

During the rising of the needles each thread is slackened by the following means: To the top tie-bar B double-armed brackets I' are secured. The back arms carry the warp-beams, each of which is provided with a grooved pulley, round which a cord is passed, one end being secured to a pin projecting from the back arm, the other end of the cord being attached to one end of a spring, having its other end hooked on a screwed pin carried by a stud in a vertical plate secured to the front arm of the warp-beam bracket, the pressure of the cord on the pulley being regulated by a thumb-nut on the screwed pin. The threads from the top warp-beam are passed over a fixed rod, J , and under a rising and falling tube, J' , then over a second fixed rod, J^2 , and through holes in a sley, J^3 , carried by studs on the top of the front guide-bar, and through the front guides to the needles. Portion of the sley J^3 is shown in plan at Fig. 10. The threads from the bottom warp-beam are passed over two other fixed rods and under a second rising and falling tube, J^4 , through sleys J^5 , and through the back guides to the needles. Portion of the sley J^5 is shown in plan at Fig. 9. The four fixed rods above named are supported at each end by uprights secured to the warp-beam brackets I' , the front arms of which latter form bearings for the ends of a rocking axle-shaft, K , which is also supported at the center of its length by a bearing secured to the top tie-bar of the machine. This axle-shaft carries an arm, K' , near each end, one of which is shown in dotted lines in Fig. 2; and to the back ends of these arms are pinned two vertical slotted plates, K^2 , which are raised and lowered by the said arms, and are guided in their movements by guide-plates K^4 or other proper means. The tubes J' and J^4 enter and are adapted to rise and fall in the slots of plates K^2 . Movement of the plate-carrying arms K' is obtained by means of an oscillatory lever, L , fixed on the left-hand end of rock-shaft K , and hinged at its free end to a connecting-link, K^3 , connected to and operated

by a crank-pin, L', carried on the outer end of cam-shaft E, as indicated in Fig. 2. The tubes J' and J⁴ are weighted by inserting therein a rod or rods of various thickness, according to the stiffness of fabric required. Each time the tubes are brought down by the slotted plates they draw off a certain portion of the threads from each beam or sets of spools, by which means the beams or sets of spools require less attention than heretofore. The tension device thus organized is simple and more effective than any tension device hitherto used of which I have knowledge. The cam-shaft E is provided at its right end with a toothed wheel, E', gearing into an intermediate wheel, which gears into a toothed wheel, E², on the end of the hand-shaft in front of the machine, by which the attendant can operate it. To the right of the wheel E' the axle-shaft is provided with a fast and loose pulley and a fly-wheel, E³. The standards A A, first named, are shorter than is required to hold the machine the proper height for the attendant, the extra height being formed by additional standards A' A' and a back tie-bar, A², secured to the bottom of the first-named standards. By such means the machine proper can be separated from the lower standards and placed entire in a case for removal. It will be seen from the foregoing that all the fabric-forming devices are carried by rocking arms which derive their movements directly from the motion-imparting cams. I thus obtain a machine of great simplicity, speed, and power as well.

The operation of the machine may be briefly described as follows: After the work has been knocked over, and as the needles rise, the slotted plates carrying the weighted tension-tube are lowered by the action of the crank-pin L', thus depressing the tubes. The plates then, by continuance of the same action, rise, and thus permit the weighted tubes to rise in the slots of the plates as the threads are lapped by the guides around the needles, and while the loops are being knocked over the needles again rise and the movements are repeated. The rocking movement of the knocking-over bits and the presser-bar with respect to that of the needles is so timed that as the needles descend the presser-bar remains in its forward position long enough to press and close the beards until their lower ends pass below the under and longer arms of the bits. The rocking frame F F' F², that carries the bits and presser-bar, then moves back in time and far enough to carry the upper and shorter ends or arms of the bits out of the path of the descending needles. This rearward rocking movement causes the under arms of the bits to knock over the previously-formed loops. The frame then again moves forward in time and far enough to bring the shorter arms of the bits over the loops in the beards of the needles, so

that as the needles rise these loops will be drawn from the beards and retained between the upper and under arms of the knocking-over bits. The upper and shorter arms of the bits thus serve to hold said loops down as the needles rise, while the under and longer arms serve as a bed for the fabric, a sley for the needles, and a knocking-over device for the loops.

Having now described my improvements, what I claim, and desire to secure by Letters Patent, is as follows:

1. The combination, with bearded needles, of knocking-over bits, formed each of a short upper and a longer lower arm, substantially as described, and operating in conjunction with said needles, substantially as and for the purposes hereinbefore set forth.

2. The combination, substantially as hereinbefore set forth, with bearded needles, of the knocking-over bits, formed each of a short upper arm and a longer under arm, substantially as described, and the presser-bar.

3. The combination, with the needles and rocking needle-carrying frame, of the knocking-over bits, formed of long and short arms, substantially as described, the presser-bar, the rocking frame carrying said presser-bar and bits, and mechanism whereby said rocking frames are operated to move with relation to one another substantially as hereinbefore set forth.

4. The guide-bars and guides, the rocker-frame carrying the same, and means for longitudinally reciprocating the guide-bars, in combination with the presser bar or bars, the knocking-over bits and bit-bar, the needles and needle-bar, and rocker-frames carrying said presser and knocking-over-bit bars and needle-bars, respectively, these parts being arranged and operated to move relatively to one another substantially as and for the purposes hereinbefore set forth.

5. The combination, substantially as hereinbefore set forth, of the weight-carrying tubes J' J⁴, the slotted plates K², and mechanism, substantially as described, for reciprocating or raising and lowering said plates.

6. The combination, with the slotted plates K², the rocking or reciprocating frame carrying the same, and one or more warp-beams, of the stationary yarn or thread guide pins and one or more intermediate weight-carrying tubes, one for each warp-beam, carried in and operated by the said plates K², substantially as and for the purposes hereinbefore set forth.

The above specification of my invention signed by me this 23d day of June, 1881.

WILLIAM CAMPION.

Witnesses:
